LACE TABLE CLOTH

Robert A. Padmore, Dunmore, Pa., assignor to The Scranton Corporation, Scranton, Pa.

Filed Apr. 9, 1970, Ser. No. 22,338

Term of patent 14 years

Int. Cl. D5—02

U.S. Cl. D92—26

The single figure is a face view of slightly more than a quarter section of a lace table cloth showing my new design, the other quarter sections being identical with that shown except the center configuration on the longer side which is as shown, the quarter sections arranged in proper relationship complete the lace table cloth. The quarter section of the table cloth is shown over a dark background to bring out the details.

I claim:

The ornamental design for a lace table cloth, as shown and described.
